(57) CLAIM

I claim the ornamental design for a display and sales package for lamp or the like, as shown.

DESCRIPTION

FIG. 1 is an isometric view of a display and sales package for lamp or the like, showing my new design;

FIG. 2 is a right elevational view thereof;

FIG. 3 is a left elevational view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines shown are for illustrative purposes only and forms no part of the claimed design.
